UNITED STATES PATENT OFFICE.

FRANCIS J. W. MAGUIRE AND THEOPHEILES LUCIER OF DETROIT, MICHIGAN.

CLAMP.

1,009,913.

Specification of Letters Patent. Patented Nov. 28, 1911.

Application filed June 29, 1910. Serial No. 569,563.

To all whom it may concern:

Be it known that we, FRANCIS J. W. MAGUIRE and THEOPHEILES LUCIER, citizens of the United States, residing at Detroit, in the county of Wayne and State of Michigan, have invented certain new and useful Improvements in Clamps, of which the following is a specification.

Our invention relates to clamping devices for holding flags and attaching them to automobiles for decorations on parades, but which may be used for other purposes.

One object of the invention is to provide an improved clamping means to engage a plurality of flag staffs or rods, the construction being such that different sized staffs may be securely held.

Another object is to provide in connection with the flag holding means an improved double clamping device capable of engaging various supports and holding the flags in different positions.

With these objects in view the invention consists in the novel features and combinations of parts hereinafter described and claimed, and illustrated in the accompanying drawings in which:

Figure 1 is a front elevation with lower portion broken away. Fig. 2 is a side elevation partly in section. Fig. 3 is an elevation of clamping member.

Our improved means for holding one or more flag staffs or other articles, comprises two clamping members A, A' in the form of plates one of which carries the other and is itself carried by the attaching or supporting means. These plates have formed in their inner faces opposing seats or grooves a to receive the flag staffs; and in order to prevent the possibility of the staffs shifting longitudinally when clamped in the seats a, the latter have molded in them spiral ribs a'. The two clamp plates may, of course, be of any shape and adapted to support a plurality of flags in any desired arrangement.

To draw the two clamp plates A, A' together and cause them to effectively bind different sized staffs, we provide screws B and opposing inclines C whereby when the two plates are drawn together they will be caused to move diagonally or angularly with respect to each other and will hence more effectively grip the flag staffs. The inclines C are here shown as being on the opposing faces of two pairs of lugs c formed on the

inner edges of the clamp plates although said inclines may be otherwise formed and located. The screws B are preferably in the form of studs fixed at one end in the removable plate A and adapted to project through slots b in the plate A' and carry thumb-nuts b' on their threaded ends. The slots b are so located that the screw studs may shift in them when the opposing inclined faces C slide on each other in tightening the thumb-nuts.

The attaching clamp consists of two members D, D' formed at their ends with jaws d, d, and d', d' and having their intermediate portions united by a screw E which serves to tighten both pairs of jaws simultaneously. The jaws d, d, are claw-like and form opposing sockets for the reception of a ball d³ which is connected by a stem d⁴ to the center of the clamp plate A. These parts, it will be observed, form a ball and socket joint between the attaching clamp and the flag holding clamp whereby the latter may be held at various angles.

The jaws d', d' are constructed for engagement with objects of different shapes. To permit them to engage a lamp bracket, fender iron or similar part of an automobile or other vehicle, their inner portions have opposing transverse grooves or seats d⁵, and to permit said jaws to engage window frames, door jambs and other places where it may be desirable to hang a flag or other article, the end portions of the opposing faces of the jaws are made flat. These flat faces may be roughened as at d⁶ if desired and they are also formed with transverse grooves d⁷ adapted to receive a nail either before or after it is driven into a support. The flat end portions of the two jaws d', d' may be formed with screw-holes d⁸ whereby the holder may be screwed to a support which cannot be engaged by the jaws.

The screw E passes through transverse openings in the two clamp members and has its head fixed against rotation in the member D as shown at e while its threaded end carries a thumb nut e'. A spring F is arranged on the screw between the clamp member and is adapted to keep the parts of the clamp in position and spread the two jaws d', d' when the nut e' is loosened. This spring is formed from a strip of resilient metal bent upon itself at f to provide spaced arms having their intermediate por-

tions apertured to receive the screw E. The extremities of the two arms of the spring are bent outwardly to provide fingers f' which enter recesses f² in the inner faces of the members D, D' and thereby prevent the spring from turning on the screw as well as cause the jaws d', d² to spread apart.

In use, the flag staffs are securely held between the clamp plates A, A' and the latter are held in the desired position by means of the attaching clamp which is double acting since the tightening of the nut e' causes the claw-jaws d, d² to grip and hold the ball in adjusted position and also causes the jaws d', d² to firmly grip a suitable support. Owing to the peculiar shape of the last named jaws, the attaching clamp may be applied to different parts of an automobile or other object and in different positions, while the ball and socket joint enables the flag holding clamp to be held in different positions with respect to the attaching clamp. The peculiar slot and screw-pin connection between the clamp plates of the flag holder and the formation of the opposing inclined surfaces on said plates, enable at least three different sized flag staffs to be effectively clamped in the device, thereby greatly increasing its range of usefulness.

30 We claim:

1. The combination of a ball provided with a stem carrying a clamp, opposing clamp members to receive a plurality of articles between them, said members having seats to receive the articles, and also having a slot and pin connection, opposing inclines on the two members to cause them to move in an angular or diagonal direction when they are drawn toward each other, means on 35 said pins for drawing the two members together, a second pair of opposing clamp members having at one end socket jaws to engage the ball, and at the other end object engaging jaws, the intermediate portions of 40 said members having recesses in their inner faces, a transverse screw arranged in the members between their ends for drawing them together and simultaneously tightening both pairs of jaws, and a spring bent 45 upon itself to provide spaced arms arranged between said members and having openings to receive said screw and bent extremities forming fingers to enter the recesses in the inner faces of said 50 members, for the purposes set forth.

2. The combination of opposing clamp members to receive a plurality of articles between them, said members having seats to receive the articles, and also having a slot and pin connection, opposing inclines on the two members to cause them to move in an angular or diagonal direction when they are drawn toward each other, and means on said pins for drawing the two members together.

3. The combination of a ball provided with a stem carrying a clamp, opposing clamp members having at one end socket jaws to engage the ball and at the other end object engaging jaws, the intermediate portions of said members having recesses in their inner faces, means connecting the intermediate portions of the members to draw them together and cause both pairs of jaws to be simultaneously tightened, and a spring strip bent upon itself to provide spaced arms arranged between said members and having 65 openings to receive said connecting means and bent extremities forming fingers to enter the recesses in the inner faces of said members, and the inner face of said jaws having transverse grooves of varying sizes. 70

4. The combination of a ball provided with a stem carrying a clamp, opposing clamp members having at one end socket jaws to engage the ball and at the other end object engaging jaws, the intermediate portions of said members having recesses in their inner faces, a transverse screw arranged in the members between their ends for drawing them together and simultaneously tightening both pairs of jaws, and a 75 spring strip bent upon itself to provide spaced arms arranged between said members and having openings to receive said screw and bent extremities forming fingers to enter the recesses in the inner faces of said 80 members, for the purposes set forth.

In testimony whereof we affix our signatures in presence of two witnesses.

FRANCIS J. W. MAGUIRE,
THEOPHEILES LUCIER.
